Peter J. Clark of Schenectady New York
Inventor

Witnessed before me this 20th day of May 1853
concerning a description in the name of the said Peter J. Clark himself
of his improvement in the process of generating heat for forging malleable iron and generating steam to propel machinery.

Be it known that I Peter J. Clark of the City of Schenectady in the County of Schenectady and State of New York have invented a new and useful improvement in the process of generating heat for forging malleable iron and of generating steam to propel machinery for the purpose of grinding and polishing iron when manufactured and for the other purposes for which steam power is generally employed.

The following is a description of the construction and operation of the furnaces and apparatus to be used in my invention. Wherever more than a cylinder boiler, or when more than one boiler is designed to be used, a given number of the furnaces of the description herein after set forth are to be erected and the same arranged in the most convenient form to receive as many points of the boiler as according to the principles herein after laid down may be deemed most expedient, as for example in circular form. The cylinder boiler however I deem best adapted to the contemplated purposes of my invention.

Where the cylinder boiler is used the number and size of the furnaces will vary according to the size of the boiler and the quantity of steam required to be raised. The furnaces are to be built in straight lines of uniform width, equidistant and continuous. The boiler to be laid horizontally or lengthways on the top of the furnaces. There is an aperture or hole in end of each furnace through which the coal is shovelled on the grate and the fire fed as occasion requires. Under each grate there is a box which I shall designate by the name of receiver, bounded above the grate from the blow pipe and the ashes falling through the grate. The receiver may be rectangular and have an opening at one end of its sides an aperture for

reaching a branch of the blast pipe. There are of course as many branches to the main blast pipe as there are furnaces and the blast pipe is connected with the bellows, which is heated by the steam the heat of the furnaces generating. The branch blast pipe enters the receiver about at its centre at a point equidistant from the grate and the bottom of the receiver thus causing the wind in the receiver to circulate equally. There is an aperture near the top of the furnace in front through which to introduce the iron to be heated. This aperture may be closed by a valve when not used.

Let the cylinder boiler be 30 feet long and two and a half feet in diameter. Then there ought to be about four furnaces, and the proportion of the different parts of the furnaces &c ought to be as nearly as may be as following - distance between the grate and the boiler twelve inches - length of grate eighteen inches, width of grate eight inches, width of the furnace to correspond with the size of the grate. The aperture at either end to admit the coal is to be eight inches in width and six inches in height. The receiver eight inches in width and six inches in height, aperture for receiving the blast pipe one inch and an half in diameter, aperture through which heat the iron intended to be worked six inches in width and three inches in height - distance between each grate three eighths of an inch. Diameter of blast pipe four inches and diminished to one inch and an half at the entrance into the receiver. The strength of the blast required is equal to that of a blacksmith's fire. The degree of heat may be regulated by valves placed in the blast pipe. I do not claim to have discovered or invented anything new in the construction of the furnaces, distinctly considered as many of the apparatus connected with the steam engine, nor can my invention in itself, if it be considered an improvement of a machine or instrument previously patented, nor can it be considered an application of an old instrument or machine to a new purpose. What I claim as new and my own invention may be reduced to the following particulars.

1° The using a number of furnaces to raise steam. 2° The process of heating the boiler uniformly at many points thus differing from the univeral practice which now obtains of heating the boiler at one particular point.

5. Employing the steam power saved by the furnace in driving the rolling
machines with steam power, 6. The application of the Blow-pipe
to ignite anthracite coal for saving steam. 7. The using the same fire
for the double purpose of raising steam and heating and working mol-
telle iron. I consider these two last particular ^{most} important and
in a special manner distinguishing my invention from every other, this
apparatus professes a highly important advantage in that it may be used
for manifold purposes, for the manufacture of malleable iron into the dif-
ferent articles usually made by blacksmiths, and edge tools, nails &c., and
the steam, ^{more} may be applied to grinding and polishing the iron when manufac-
tured, to propelling boats, driving a ship, horses & mills of every descrip-
tion and the other purposes for which steam power is generally employed.
